LENS MEASURING INSTRUMENT

Charles J. De Grave, Jr., Chili, N. Y., assignor to Bausch & Lomb Optical Company, Rochester, N. Y., a corporation of New York

Application February 19, 1954, Serial No. 29,128

Term of patent 14 years

(Cl. D57—1)

FIG. 1

FIG. 2

Fig. 1 is a perspective view of a lens measuring instrument showing my new design.

Fig. 2 is a perspective view of the other side of the instrument with the view taken in the opposite direction.

The essential features of my design are shown in full lines on the drawing.

I claim:

The ornamental design for a lens measuring instrument, substantially as shown and described.
